J. M. DEITRICH.

AEROPLANE.

APPLICATION FILED SEPT. 17, 1913.

1,157,371.

Patented Oct. 19, 1915

UNITED STATES PATENT OFFICE.

JOHN M. DEITRICH, OF BATTLE CREEK, MICHIGAN.

AEROPLANE.

1,157,371.

Specification of Letters Patent.

Patented Oct. 19, 1915.

Application filed September 17, 1913. Serial No. 790,188.

To all whom it may concern:

Be it known that I, JOHN M. DEITRICH, a citizen of the United States, and a resident of Battle Creek, in the county of Calhoun 5 and State of Michigan, have made certain new and useful Improvements in Aeroplanes, of which the following is a specification.

My invention relates to improvements in 10 aeroplanes, and it consists in the constructions, combinations and arrangements herein described and claimed.

An object of my invention is to provide a device by means of which the aeroplane 15 may be safely brought to earth in case of accident. To this end I construct the main sustaining plane in the form of a curve and so place the various parts of the device that the weight is symmetrically disposed about 20 the center of gravity.

A further object of my invention is to provide means for propelling the device in which the propellers are located at both the front and the rear thus exerting a push and 25 a pull.

Other objects and advantages will appear in the following specification and the novel features of the device will be particularly pointed out in the appended claim.

30 My invention is illustrated in the accompanying drawings forming part of this application in which—

Figure 1 is a side view of the device, Fig. 2 is a bottom plan view, and Fig. 3 is a section along the line 3—3 of Fig. 1.

In carrying out my invention I provide a main frame consisting of the longitudinal members 1, the uprights 2, cross members 3, and braces 4. At the end of the cross mem- 40 bers are disposed wheels 5.

The bottom of the device consists prefer- ably of a board 6 which is secured to the cross members 3 between the uprights 2. At the top of the uprights 2 is the main sustain- 45 ing plane 7. This plane, as will be seen from Figs. 1 and 3 is curved and is inclined down- wardly from the front to the rear.

Carried upon the bottom 6 are two motors 8 and 9, the motor 8 being connected by 50 means of the chain 10 with a shaft 11 upon which the rear propeller 12 is disposed. The motor 9 is connected by means of a chain 13 with a shaft 14 upon which the front pro-

peller 15 is disposed. In the rear of the rear propeller 12 is the horizontal elevating plane 55 16, the rudder 17 being disposed in the rear of the elevating plane. The rudder and the elevating plane are manipulated by means of flexible cords 18 and 19 respectively.

Various parts of the machine such as the 60 motors 8 and 9, propellers, elevating planes, rudder, wheels, etc., are disposed symmetrically about the center of gravity of the device.

From the foregoing description of the 65 various parts of the device the operation thereof may be readily understood. The provision of the two engines causes a push and a pull to be given to the machine. If one engine is out of commission the other 70 can be used to propel the device. It will be observed that the plane 7 is disposed longitudinally of the machine and therein it differs from other aeroplanes. The curved form of the planes 7 makes of the latter a 75 parachute, so that if for any reason it is desired to descend the device will settle easily to the ground while maintaining its horizontal position. The upward inclination of the plane 7 tends to cause an upward lift 80 when the device is propelled forwardly.

I claim:

In an aeroplane, a main frame, a main sus- taining plane carried by said main frame and extending longitudinally of said main 85 frame, said main sustaining plane being curved laterally and being inclined from its rear edge to its front edge, a bottom sup- port carried by said frame, a pair of motors carried by said bottom support, a pair of 90 propellers, one of said propellers being dis- posed in the rear of said sustaining plane and being driven by one of said motors, and the other propeller being disposed in front of said main sustaining plane and being 95 driven by the other motor, an elevating plane in the rear of one of said propellers, a rudder in the rear of the elevating plane, said motors, propellers, elevating plane, and rudder being disposed symmetrically about 100 the center of gravity of the device.

JOHN M. DEITRICH.
